CLAIM

The ornamental design for a bath spout cover, as shown and described.

DESCRIPTION

FIG. 1 is a perspective view taken from the top, front, and left side of the bath spout cover of the present invention;

FIG. 2 is a left side elevational view of the bath spout cover of FIG. 1, the opposite side being nearly a mirror image thereof;

FIG. 3 is a bottom plan view of the bath spout cover of FIG. 1;

FIG. 4 is a top plan view of the bath spout cover of FIG. 1;

FIG. 5 is a front elevational view of the bath spout cover of FIG. 1; and;

FIG. 6 is a rear elevational view of the bath spout cover of FIG. 1;
